(57) **CLAIM**

The ornamental design for a wire guide, as shown and described.

DESCRIPTION

FIG. 1 is a side perspective view of the wire guide showing my new design;

FIG. 2 is a bottom plan view thereof;

FIG. 3 is a top perspective view thereof;

FIG. 4 is a top plan view thereof;

FIG. 5 is a side elevation view thereof; and,

FIG. 6 is a front elevation view.

The broken line disclosures shown in the Figures of the wire guide are for illustrative purposes only and form no part of the claimed design.
